PAUL KLEIN, OF BUDAPEST, HUNGARY, AND ANDREW SZEGVARI, OF AKRON, OHIO,
ASSIGNORS TO AMERICAN ANODE INC., OF AKRON, OHIO, A CORPORATION OF DELA-
WARE

MANUFACTURE OF RUBBER GOODS FROM RUBBER DISPERSIONS

Application filed April 13, 1927, Serial No. 183,606, and in Hungary and Germany April 14, 1926.

In the manufacture of rubber goods by electrophoretic precipitating of rubber from rubber dispersions on the anode, or on a precipitating backing or support surrounding the anode, gases are liberated at the cathode owing to the electrolysis which takes place simultaneously with the cataphoresis. The gas bubbles escaping from the cathode may reach the rubber precipitate and adhere to it, thereby impairing the uniformity of the rubber coating. Although it is possible to prevent the gases liberated at the cathode from reaching the rubber precipitate by inserting deflecting walls or diaphragms between the cathode and the precipitating backing, this method may be unsuitable, or even impracticable under certain conditions, especially in the manufacture of closed hollow articles such as inner tubes of tires.

According to this invention in the cataphoretic device means are provided to prevent the liberation of gas at the cathode during cataphoresis. For example means acting at the cathode may be used suppressing the generation of hydrogen. For this purpose oxidizing depolarizing agents may be used.

According to this invention, preferably a cathode is used, the surface of which consists of a metal oxide, which is easily reduced, for example, lead peroxide. The hydrogen ions discharging at the cathode reduce this oxide surface. Preferably the cathode consists of lead, the surface of which has been converted to lead peroxide, for example, by means of the well known storage battery process. After the lead peroxide cathode has been used, it can be inserted as the anode in a suitable bath, and then polarized by re-oxidation so that it can be used again.

An example of the new method applied to the manufacture of inner tubes is described with reference to the annexed drawing.

Fig. 1 is a sectional elevation of an apparatus for the manufacture of inner tubes.

Fig. 2 is a plan view.

11 is a metallic mold in the shape of a hollow ring consisting of two halves, 11-a and 11-b, preferably having a removable lining, for example, of zinc. The two halves 11-a

and 11-b, of the mold are detachably joined in any suitable manner, for example, by bolts 17. 1 is the annular cathode within the mold which is interrupted at 19 and has a shaft 7 to attach the cathode to the mold. The cathode consists preferably of an iron tube with an outer coating of lead. The layer of lead is formed in the well known manner, which is used for storage battery plates so that a porous layer of lead peroxide is generated on its surface. In order to prevent the crumbling of this surface coating, the cathode can be covered with a protective coating of any material permeable or semi-permeable to liquids, for example, a coating of gelatin. The tubular cathode is preferably provided with an opening 16 diametrically opposite to the shaft 7, or with a plurality of openings. The shaft 7 of the cathode is inserted in the mold and sealed water-tight by means of a stuffing box 8 having an insulating lining. It can be firmly attached to the carrier 5 by means of any suitable device, for example, the threaded box 4 having insulating linings 2 and 6. The carrier 5 is rigidly connected to the one part 11b of the mold in an exactly centered position. The stuffing box 8 is provided with an air outlet pipe 9 which can be closed if necessary. The whole device is journaled by means of the diametric carrier 10 and bolts 12 in pivot 14 of support 15 so that it can be rotated around the horizontal axle 13.

The manner of operating the apparatus is as follows:

When the mold has been put together as described above, and is in the horizontal position, it is filled through the tubular cathode 1 with the rubber dispersion. This rubber dispersion enters the mold through the opening 16, and the air escapes from the mold through the tube 9. When the hollow of the mold is filled with rubber dispersion up to the level of the mouth of the tube 9, the tube 1 is attached by the terminal 3 to the negative pole of a source of current, and the mold 11 is attached by terminal 20 to the positive pole so that the rubber is precipitated on the inner wall of mold 11. The liquid can also circulate continuously through the mold during the cataphoresis and escape at 9, but it is

preferable to check the circulation so that only the necessary amount of flow is maintained to permit formation of a uniform precipitate.

5 By suitable choice of the metal of the inner wall of the mold 11, for example by use of zinc, and by suitable composition of the rubber dispersion, formation of gas at the anode can be prevented in the well known manner. 10 It will be understood that the electrophoretic precipitation must be conducted as known per se in such a way that no gas is developed on the precipitation surfaces. For this purpose instead of using metallic precipitating molds, a porous non-conducting water permeable depositing mold can be used, for example, in the manner described in Patent No. 1,548,689. This non-conducting mold can be connected to the electroconductive anode by 15 a layer of electrolyte, either free or absorbed in a non-liquid material. The hydrogen ions discharging at the cathode 1 are combined with the lead peroxide layer on the cathode so that no gases are set free in the hollow 20 of the mold.

When a relatively thick precipitate has been formed, the flow of rubber solution through the tube 1 is stopped, and the mold is rotated on the pivot 13 to an angle of about 30 180° in the direction of the arrow 21 into the position indicated by chain lines. In this way the stuffing box 8 with the tube 9 is turned downwards. The liquid is then drained from the mold up to a residue of a few drops. The 35 tube 1 can then be connected to a hot air conduit so that the hot air enters through the opening 16 of the cathode and escapes through tube 9, thus circulating through the mold and drying the precipitated rubber. The mold is 40 then opened. After loosening the threaded box 4, the shaft 7 is disconnected from the cathode, and the elastic hollow tube formed by precipitated rubber can be removed from the mold together with the cathode in its interior. The elastic annular tube can be 45 stripped off from the cathode owing to the interruption 19 of the ring forming the cathode. The tube made in this manner can be cured in the usual way. The term, "rubber 50 dispersion," includes all natural or artificial, vulcanized or unvulcanized dispersions of rubber, gutta percha, balata, and the like vegetable resins with or without conditioning substances.

55 Having now particularly described and ascertained the nature of our said invention and in what manner the same is to be performed, we declare that what we claim is:—

1. The process for the manufacture of 60 hollow rubber goods from aqueous dispersions of rubber by electrodeposition of rubber which comprises filling with an aqueous dispersion a closed container constituting the anode, electrodepositing a rubber layer 65 from the aqueous rubber dispersion utilizing

a cathode immersed in the aqueous dispersion and capable of inhibiting escape of gas at the cathode, whereby gases normally liberated at the cathode are prevented from entrainment with the deposited rubber layer. 70

2. The process for the manufacture of hollow rubber goods from aqueous dispersions of rubber by electrodeposition of rubber with an exterior mold-formed surface which comprises confining a body of the aqueous dispersion in a closed container constituting the anode, preparing a cathode by associating with it a depolarizer, electrodepositing a rubber layer from an aqueous rubber dispersion utilizing said prepared cathode immersed in the dispersion whereby gases normally liberated at the cathode are reduced by said depolarizer and inhibited from entrainment with the deposited rubber layer. 75 80

3. The process for the manufacture of hollow rubber goods from aqueous dispersions of rubber by electrodeposition of rubber which comprises confining a body of the aqueous dispersion in a closed container constituting the anode, electrodepositing a rubber layer from an aqueous rubber dispersion utilizing a lead peroxide-coated cathode immersed in such dispersion, whereby gases normally liberated at the cathode react with the lead peroxide and are inhibited from entrainment with the deposited rubber layer. 90 95

4. The process for the manufacture of hollow rubber goods from aqueous dispersions of rubber by electrodeposition of rubber with an exterior mold-formed surface which comprises confining a body of aqueous dispersion in a closed container constituting an anodic surface of an electric cell, depositing by an electric current traversing said dispersion through the intermediary of a cathode 100 immersed therein a layer of rubber upon said surface, and reducing the gases formed at the cathode to inhibit the entrainment of gases in the rubber layer deposited. 105

5. The steps in the process of making hollow rubber articles by electrodeposition from aqueous rubber dispersions with an exterior mold-formed surface which comprises confining a quantity of aqueous dispersion in contact with surface capable of producing 110 the exterior contour of the hollow article, depositing by an electric current traversing the said dispersion through the intermediary of a cathode immersed therein a layer of rubber upon said surface, and oxidizing the 115 gases formed at the cathode to inhibit their entrainment in the rubber layer deposited, whereby gases normally liberated at the cathode are reacted with said agent and inhibited from entrainment with the deposited 120 rubber layer. 125

6. Apparatus for the manufacture of hollow articles comprising a mold adapted to contain an aqueous dispersion of rubber, and having an interior anodic surface upon 130

which a layer of rubber is adapted to be deposited by electrophoresis, a cathode disposed within said mold, and means associated with the cathode for preventing the liberation of gases formed at the cathode,
5 whereby gases normally liberated at the cathode are inhibited from entrainment with the deposited rubber layer.

7. Apparatus for the manufacture of hollow articles comprising a mold adapted to contain an aqueous dispersion of rubber, and having an interior anodic surface upon which a layer of rubber is adapted to be deposited by electrophoresis, and a lead cathode disposed within said mold having a surface coating of lead peroxide, whereby gases normally liberated at the cathode are reacted with said agent and inhibited from entrainment with the deposited rubber layer.

8. Apparatus for the manufacture of hollow articles by electrophoresis comprising a sectional mold having a small duct communicating with the outside when sections are closed, and a hollow cathode disposed within said mold and provided with means for the passage of aqueous dispersion of material to be deposited therefrom into the mold, whereby said dispersion can be supplied to and distributed in said mold prior to and
25 during the electrophoretic action.

9. Apparatus for the manufacture of hollow articles by electrophoresis comprising a sectional mold having a small opening when sections are closed, and a hollow cathode
35 substantially centrally disposed within said mold when its sections are united and provided with means for uniformly distributing a fluid in and through the mold, whereby said dispersion can be supplied to and distributed in said mold prior to and during the electrophoretic action.

10. Apparatus for the manufacture of hollow annular articles by electrophoresis comprising an annular sectional mold comprising an anode, and an annular cathode disposed within the mold, and insulated therefrom and means associated with the mold and the cathode for circulating the material to be deposited through the mold.

11. Apparatus for the manufacture of hollow annular articles by electrophoresis comprising an annular sectional mold comprising an anode, and an annular cathode disposed within the mold and insulated therefrom, and means associated with the cathode for inhibiting the liberation of gases formed at the cathode.

In testimony whereof we affix our signatures.
